UNITED STATES PATENT OFFICE.

CLIVE PEMBERTON CURLEWIS, OF SYDNEY, NEW SOUTH WALES, AUSTRALIA.

SHEET-METAL REINFORCING MEMBER FOR CONCRETE AND PLASTER.

1,245,198.

Specification of Letters Patent.

Patented Nov. 6, 1917.

Application filed July 21, 1915. Serial No. 41,144.

To all whom it may concern:

Be it known that I, CLIVE PEMBERTON CURLEWIS, a subject of the King of Great Britain and Ireland, residing at 12 Castle-reagh street, Sydney, New South Wales, Australia, have invented certain new and useful Improvements in Sheet-Metal Reinforcing Members for Concrete and Plaster, of which the following is a specification.

This invention relates to reinforcing members for building structures, produced by slitting and forming flat metal sheets without "expanding" them, and it has for its object to provide a reinforcing element in which the metal is disposed to maximum advantage to support the plaster or cement surfaces spread upon it, and to secure rigidity sufficient to enable a wall structure to be erected without using studding supports to carry the reinforcement. It is a further object of my invention to effect the manufacture of such reinforcing elements at minimum cost, to which end my particular structure of reinforcing member has been designed so that it may be produced in a single machine operation in which the metal is at once slit and bent.

According to my invention a flat sheet of metal of appropriate gage for the particular service required is divided longitudinally for the greater part of its length by slitting it in parallel lines, and the slitted portions are bent transversely of their length to form rigid ribs the ends of which are carried by the uncut portions of the sheet which form transverse connecting members of the structure. Longitudinal rigidity is thus attained, and transverse rigidity, when required, is attained by bending the transverse connecting members transversely of their length. Transverse rigidity may be increased when required, by first folding these transverse portions of the sheet and then bending them.

My reinforcing element is thus constituted of longitudinal ribs connected by transverse flats or ribs without "expanding" the sheet. Where the sheet is of considerable length one or more transverse connecting members may be used in addition to the transverse members at the ends of the sheet.

My invention is distinguished from known forms of sheet metal reinforcement by the fact that the metal sheet is not "expanded" during or after slitting, and that long longitudinal ribs formed by transversely bending

slitted portions of the sheet are connected together and supported at their ends by transverse members which may also be bent transversely of their length to augment transverse rigidity of the element.

Metal sheet reinforcements according to this invention may be produced and erected at a cost which competes with the cost of wood lathing. This result is attained because the design of the reinforcement is such that it may be produced in a single machine operation and that a low grade of metal may be used in view of the fact that the metal is not so stressed or distorted in the manufacturing operation as to weaken or fracture it.

In the accompanying drawings, Figure 1 is a perspective view of portion of a sheet of reinforcement according to my invention in which the transverse members are flat and the slitted portions are pressed to a section approximately parabolic, tapering away at the shoulders.

Fig. 2 is a similar perspective view exhibiting a form of transverse members which procures transverse rigidity, and exhibiting also holes punched in the shoulders of the longitudinal members to facilitate the pressing of said member to parabola-like section without rupturing the metal in the locality of the transverse member.

Fig. 3, is a similar perspective view showing the longitudinal ribs formed to trough section by bending their edges and showing also the transverse member doubled and bent to augment transverse rigidity.

Fig. 4 is a perspective view of a sheet of reinforcement according to my invention with a transverse connecting member intermediate between the end connecting members and the three transverse members set up on rods to maintain them in alinement and sustain vertical load, and augment lateral stability.

These reinforcing members are suitable for the erection of divisional walls and light exterior walls and also in the construction of roofs and ceilings. Incidentally also the form of reinforcement shown in Fig. 1, in which the lateral members are flat, has a utility as a packing for goods requiring special protection during carriage, as this form of reinforcement may be rolled transversely of its length.

When these reinforcing elements are fixed to studs or to ceiling rafters or the like by

nailing, the transverse connecting members may be flat as shown at A, Fig. 1. When, however, they are required to be erected without studding, and with the ribs B in a horizontal plane, the transverse members are bent to form a hollow section as shown at C (Figs. 2, 3 and 4). As shown in Fig. 3, the transverse bent member C may be doubled to further stiffen it, and thereby better enable the reinforcement to carry the weight of the plaster facing and to augment lateral stability, the ends of the sheets being so doubled over before the sheets are inserted in the slitting and forming machine. When the ribs B are pressed to a parabola or similar curved section as shown in Figs. 1 and 2, bursting of the metal at the shoulders E is prevented by punching holes F through the shoulders simultaneously with the slitting of the sheets so as to give maximum facility for flow of metal in the forming operation about those points.

In Fig. 4 H are metal rods to which sheets of the reinforcement with bent transverse members are applied by laying the same on to those rods, so that the rods will be embraced in the concaves of said transverse members C. The sheets are secured to the rods by wire ties as shown at K. A sheet of considerable length as shown at Fig. 4 may have intermediate of its transverse end members C one or more intermediate transverse members L.

The particular section to which the ribs are bent or pressed is not an essential of the invention so long as they are bent or pressed to form regular sections insuring longitudinal rigidity between their ends.

Copies of this patent may be obtained for five cents each, by addressing the "Commissioner of Patents, Washington, D. C."

which are supported by the transverse members. Thus they may be formed either to parabola or like section as in Fig. 1 or to trough section as in Fig. 2, or the parabola type of section as shown in Fig. 1 may be modified to V-section.

Subject to limitations dictated chiefly by the relative thickness of the metal and length of the ribs, the several forms of reinforcement illustrated are usable for purposes of reinforcing concrete and similar structures generally.

What I claim as my invention and desire to secure by Letters Patent is:

1. A reinforcing element constructed of flat sheet metal slitted longitudinally to form parallel slats extending longitudinally to points near the ends of the sheet, the edges of said slats being bent to form said slats into rigid parallel ribs the ends of which are supported by uncut transverse portions of the sheet, and said uncut portions at the ends of the sheet consisting of ribs of double thickness of metal.

2. A reinforcing element comprising a metal sheet having uncut portions, upwardly pressed, parallel slats contained between said uncut portions and having shoulders at their junctions therewith, and holes punched near said shoulders to facilitate flow of metal in the pressing operation and thereby diminish risk of fracturing said metal.

In testimony whereof I have affixed my signature in presence of two witnesses.

CLIVE PEMBERTON CURLEWIS.
